(57) **CLAIM**

The ornamental design for a smart lock, as shown and described.

DESCRIPTION

FIG. 1 is a front elevational view of a smart lock, showing my new design;

FIG. 2 is a rear elevational view thereof;

FIG. 3 is a left elevational view thereof;

FIG. 4 is a right elevational view thereof;

FIG. 5 is a bottom plan view thereof;

FIG. 6 is a top plan view thereof;

FIG. 7 is a front, left, and bottom perspective view thereof; and,

FIG. 8 is a rear, left, and top perspective view thereof. The broken lines depict portions of the smart lock and form no part of the claimed design.
